*Primary Examiner—Bernard Ansher**Assistant Examiner—P. Hyder**Attorney, Agent, or Firm—Davis, Bujold & Streck***[57] CLAIM**

The ornamental design for piston compression pressure sensor, as shown.

DESCRIPTION

FIG. 1 is a left side elevational view of a piston compression pressure sensor showing my new design;

FIG. 2 is a front elevational view thereof;

FIG. 3 is a rear elevational view thereof;

FIG. 4 is a perspective view thereof;

FIG. 5 is a bottom plan view thereof; and,

FIG. 6 is a top plan view thereof.

FIG. 1. FIG. 2. FIG. 3. FIG. 4.

FIG. 5.

FIG. 3.

FIG. 6.
